GRANVILLE WOOD, OF DETROIT, MICHIGAN.

Letters Patent No. 67,150, dated July 23, 1867.

IMPROVEMENT IN MELODEONS.

The Schedule referred to in these Letters Patent and making part of the same.

TO ALL WHOM IT MAY CONCERN:

Be it known that I, GRANVILLE WOOD, of Detroit, in the county of Wayne, and State of Michigan, have invented certain Improvements in Melodeons and other reed instruments of music; and I do hereby declare that the following is a full and exact description thereof, reference being had to the accompanying drawings, making part of this specification—

Figure 1, being a vertical section from front to back of the air-chamber of a melodeon and the adjacent parts, to which my improvement directly relates.

Figure 2, a front view of a corresponding portion of a melodeon.

Figure 3, a back view of a similar part of a melodeon, a portion of the back partition being removed.

Figure 4, a top view of a portion of the reed-board of the instrument.

Like letters designate corresponding parts in all of the figures.

The tones of reed instruments are very sensibly affected not only by the quantity of air which passes through them, but both by the velocity of the air and the direction in which it impinges upon them. Thus, with the usual constructions of melodeons, when the swell is opened, the higher and lower reeds, if before tuned in harmony, immediately become differently affected by the increased volume of air, and are discordant. Hitherto no completely effectual remedy has been devised; and since perfect accord could be obtained only in one condition, a compromise has been adopted by tuning the reeds to an even temperament between the concords and discords, thus rendering both somewhat discordant.

The object of my invention is to take advantage of the circumstances of the velocity and the direction of the air as it comes to the reeds, for the purpose of correcting the usual discordant effect of the variation in the volume and velocity of air produced by the swell, and also, in double-reed instruments, to add variety by varying the quality of the different sets of reeds. At the same time an object has been not to increase the size or otherwise materially change the usual dimensions, form, or proportions of such instruments as adopted by the best manufacturers.

The means by which I accomplish my purposes are, first, the enlargement of the capacity of the air-chamber above the reeds; second, the location of the reeds in the air-chamber at a greater distance from the swell; and third, the use of a wind-shield over the reeds, to check, diffuse, and equalize the motion of the air as it approaches the different reeds, all substantially as hereinafter specified.

In the accompanying drawings, let A represent the key-board or keys of a melodeon. I occupy the entire space under the key-board, and to as great a depth as may be without encroaching on that of the bellows below, with the air-chamber C, into which the air is let before passing through the reeds F F. For convenience in arranging the reeds to suit my purpose, I locate the swell B in front of the key-board, as shown, but I lay no claim to this mere position, and the swell may be located behind the key-board as usual. But whatever the position of the swell B, I locate the reeds F F as far from (in the case represented as far back from) the swell as the construction will conveniently permit. Then I extend the cap-board D over the reeds as shown, there being a cavity under that edge thereof, so as to admit the air, but thus requiring the air first to pass backward from the swell over this board and completely reverse its direction before reaching the reeds, thereby becoming equalized in velocity throughout the extent of the reed-board and softened in effect upon the tones of the reeds. When two sets of reeds are used, I locate them in the same chamber, C, with the reeds F F; and, since the changing of the direction of the air, as it strikes the reeds, softens and rounds the tones, and it is usual to voice the additional set of reeds to somewhat coarser and louder tones than the other set, I produce this effect very happily and perfectly by letting the air directly from the swell upon them. Or if the direction of the air on both sets should be varied, one would be varied more than the other. The two sets of reeds being in one chamber harmonize better than if in separate chambers. The effect of thus having a large air-chamber, C, from which to supply the reeds, and of removing the reeds from the direct influence of the currents of air admitted by the swell is not only to obviate the discordance produced on the high and low reeds, in varying the force of the blast, but to make the tones of all the reeds rounder, fuller, and clearer. The operation of the air may be compared with that of the flow of water, wherein the action of the large air-chamber C, as compared with the ordinary smaller air-space, is similar to that of a lake from which the water is drawn at many

different places, compared with that of a stream, the current of which at different places varying in rapidity, has different effects in flowing out.

I do not claim the simple enlargement of the air-space between the swell and the reeds of a melodeon or other reed instruments as a mere variation of size, without change of construction, since in ordinary melodeons there is, strictly speaking, no such chamber, but only a narrow passage. Nor do I claim the employment of an air-chamber below the reeds, as my invention is intended to modify the movements of the air before it strikes the reeds.

What I claim as my invention, and desire to secure by Letters Patent, is—

The employment of an air-chamber, C, over the reeds F F, when the reeds are placed and arranged therein in such a manner that they do not receive the currents of air admitted by the swell direct, but changed in direction and equalized in force, substantially as and for the purposes specified.

The above specification of my improvements in melodeons and other reed instruments signed by me this twenty-sixth day of December, 1866.

GRANVILLE WOOD.
